UNITED STATES PATENT OFFICE.

JOSEPH A. DALTON, OF PAWTUCKET, RHODE ISLAND, ASSIGNOR OF ONE-HALF TO
PETER J. QUINN, OF PAWTUCKET, RHODE ISLAND.

DRILL-CHUCK.

973,345.

Specification of Letters Patent. Patented Oct. 18, 1910.

Application filed January 6, 1910. Serial No. 536,670.

To all whom it may concern:

Be it known that I, JOSEPH A. DALTON, a citizen of the United States, residing at the city of Pawtucket, in the county of Providence and State of Rhode Island, have invented certain new and useful Improvements in Drill-Chucks, of which the following is a specification.

My invention relates to an improved structure in that class of tools for holding drills; and the objects in view are to simplify the structural parts of the chuck, and to have the body of the tool free to be gripped upon to permit a drill to be easily released or mounted in position during the revolving movement of the tool in a machine-spindle, of the novel construction, arrangement, and combination of parts, as hereinafter described and claimed.

20 In the accompanying sheet of drawings, Figure 1 represents a sectional view of a drill-chuck, as constructed in accordance with my invention. Fig. 2 is a plan section taken on line 2.—2. of Fig. 1, showing arrangement of spring connection for the tool-body and its support. Fig. 3 is a plan section taken on line 3.—3. of Fig. 1, showing the cam arrangement for forcing rolls into frictional contact upon the shank of the 30 drill. Fig. 4 is a side elevation of the fixed support for the tool-body, together with means for releasing the rolls from engagement with the drill-shank, and, Fig. 5 is a plan section taken on line 5.—5. of Fig. 4.

35 Like reference characters indicate like parts.

a designates the tool-stock which has at its lower portion an enlarged integral circular collar a¹.

40 b is the tool-body, of cylindrical form, having a circular recess formed in its top face, as at b¹, to receive the stock-collar a¹, and said body is provided with an opening therethrough from said recess, the upper part of said opening being a concentric bore to act as a chamber, as b², for the reception of a coil spring s and the lower part of said opening arranged to dispose three cam faces, as at points b³, b⁴, b⁵ in Fig. 3, that form 50 bearing surfaces for three rollers r, r, r.

55 c is the support for the tool-body b, said support having a cylindrical shank c¹ which is reduced in diameter to form a screw-threaded portion c² to engage in a threaded aperture of the stock-collar a¹, said support

has three legs c², c², c² divided equidistantly apart throughout the circle of said support, depending from the shank c¹ of the latter, and which legs terminate with an enlarged concentric head c³ having a reduced portion c⁴ to fit within a second concentric bore formed at the bottom of the tool-body, as at b⁴, and leave a shoulder on said head, as c⁵, to abut the bottom end face of said body, in the manner shown in Figs. 1, 4 and 5. The head c³ of the member c, is provided with a central opening c⁶ to freely receive the shank d¹ of the drill d. The spring s surrounds the shank c¹ of the support c, the upper end of said spring being made fast in said shank, as at a point s¹ in Fig. 2, while the lower end of said spring is made fast in the tool-body b, as at a point s² in said figure. The tool-body b is loose between the stock-collar a¹ and head c³ of the fixed support c, and the legs c² of the latter are designed to fit between the friction rollers r. The surface of the cams b³ extend from the concentric bore b⁴ of the tool-body b to a point near to and below the shank c¹ of the support c.

Assuming the tool to be mounted in a machine-spindle and to revolve continuously in the direction indicated by the arrow: When desired to insert a drill the operator grasps the body b with a hold sufficient to cause a contracting of the spring s and at the same time permit the rollers r to move to their lowest position on the cam surfaces b³, when the shank d¹ of the drill may then be readily inserted within the support c, after which the operator releases his grasp upon the body b when the expanding action of the spring then causes the rollers r to move along the increase of rise of the cams and into firm frictional contact upon the surface of the drill-shank. Therefore, by having the tool-body b free to grasp upon and turn against the tension of the spring s permits a drill to be readily inserted and held in a rigid position during the revolution of the tool.

100 What I claim and desire to secure by Letters Patent, is—

In a tool of the class described, the combination of a stock having an integral collar which is provided with a screw-threaded aperture; a body having a circular recess to receive the stock-collar and said body having an opening extending from its recess, the upper part of said opening in the form of a circular chamber, and the lower part of said

opening arranged to dispose three cam bearing surfaces; a cylindrical roller mounted on each cam surface; a cylindrical supporting member having a shank which is reduced to form a screw-threaded portion to engage in the threaded aperture of the stock-collar, said member having three legs depending from its shank and which legs terminate with a circular head having a reduced portion to fit a bore formed in the front face of the tool-body, and said member provided with an opening formed in its head to re-

ceive the drill-shank; and a coil spring in the chamber of the tool-body and surrounding the shank of the supporting member, and said spring having one end attached to the latter and its other end attached to said tool-body.

In testimony whereof I affix my signature in presence of two witnesses.

JOSEPH A. DALTON.
